UNITED STATES PATENT OFFICE.

HENRY P. MERRIAM, OF NEW YORK, N. Y.

FUSE FOR PROJECTILES.

No. 822,289.

Specification of Letters Patent.

Patented June 5, 1906.

Application filed June 23, 1905. Serial No. 266,609.

To all whom it may concern:

Be it known that I, HENRY P. MERRIAM, a citizen of the United States, residing at New York, in the county and State of New York, 5 have invented certain new and useful Improvements in Fuses for Projectiles, of which the following is a specification.

My present invention relates to improvements in the type of projectile-fuses illustrated in my United States Letters Patent Nos. 770,084, 770,182, and 770,183, all granted September 13, 1904. The underlying principle of the type of fuse set forth in these patents is the control of the arming of a 15 percussion-fuse by means of a series of centrifugally-released controlling devices, which are so arranged relatively that each controlling device is incapable of individual movement, while all controlling devices are free to 20 move simultaneously by the action of said centrifugal force for arming the fuse. The forms of fuses shown in my prior patents have been practically tested and have proven highly efficient for the purposes intended.

The purposes of my present invention are to improve and simplify the construction and reduce the cost of manufacture of projectile-fuses of this type and at the same time maintain the high efficiency of safety and certainty of action of such fuses. In constructing this type of fuse in the past I have employed a suitable hollow fuse-casing supporting one or more primers, one or more firing-pins movably supported in the casing in operative relation to the primer or primers, a spherical hammer freely mounted in the casing in proper relation to the firing pin or pins, a securing-pin also movably mounted in the casing and engaging the hammer and firing pin or pins, and a series of interlocking centrifugally-actuated controlling devices mounted in the casing and arranged to normally lock the securing-pin against movement and adapted when released by centrifugal force to free the securing-pin, and thereby arm the fuse. In this old form of fuse the controlling devices are in the form of radially-movable cylindrical blocks having some suitable interlocking means for preventing their individual movement and insuring their simultaneous movement under the action of centrifugal force.

The improved form of fuse covered by the present application embodies the general principle of the old form as covered, broadly, 55 in above patents, Nos. 770,084 and 770,182,

above referred to; but specifically the new form of fuse differs materially from the old form.

In the new form of fuse I provide a longitudinally-movable plunger within the fuse-casing, and upon or within this plunger, I mount the primer, the relatively movable combined firing-pin and plunger-securing pin, and the centrifugally-actuated, interlocked controlling devices, which are only capable of joint action. The plunger comprises, preferably, a sheet-metal thimble or casing, snugly surrounding a core-piece, which is properly recessed to support the operative parts of the fuse. In a central recess at the lower end of the plunger is mounted a suitable primer, and communicating with the primer-cavity is a longitudinal passage-way, in which is mounted the reduced lower end of the combined firing-pin and plunger-securing pin. This combination-pin is formed with an enlarged upper end, which affords an annular locking-shoulder, with which engage the plurality of centrifugally-released controlling devices. These controlling devices rest in individual angular channels or recesses extending longitudinally in the plunger in planes radial to the plunger-axis, each recess being inclined slightly from the longitudinal axis, so that the inner faces of the upper locking ends of the controlling devices can surround or partially surround the combination-pin referred to and engage the annular shoulder for locking the said pin against movement within the plunger. Each of the controlling devices rests upon the lower edge of one of the oblong openings cut into the sheet-metal casing of the plunger in registry with the angular recesses of the plunger core, and in the operation of said parts their outer faces are projected through said oblong openings by the centrifugal action and caused to bear frictionally against the inner wall of the cavity of the fuse-casing to exert a retarding influence upon the forward movement of the plunger in the fuse-casing during the flight of the shell. Each controlling part is shaped to fit freely in one of the angular recesses of the plunger with its locking end in engagement with the combination-pin. A small leaf-spring rests in a longitudinal groove in the outer face of each controlling part, one end of the spring being fixed to the controlling part and the other end engaging beneath the plunger-casing.

To prevent individual movement of the

controlling parts and insure their simultaneous movement under the action of centrifugal force, I cut into the upper end of each controlling part two grooves or channels, which extend at angles of thirty degrees to radial planes of the plunger, in which radial planes the controlling parts move. These grooves or channels are so arranged in the adjacent controlling parts that the adjacent grooves will be in alinement so long as the parts move in unison. Resting in each contiguous pair of grooves or channels of adjacent controlling parts is a thin sheet-metal controlling-plate formed with an upwardly-projecting central lug or shoulder, which rests in a radial slot cut in the end of the plunger-casing. By reason of this arrangement it will be observed that each of the controlling-plates can be moved only in a line radial to the center of rotation of the fuse. It will also be observed that in moving from closed to open position the contiguous grooves or channels of adjacent controlling parts are always at right angles to this radial line on which the engaged controlling-plate moves, so that the controlling parts will not bind upon the controlling-plates so long as the controlling parts are moved simultaneously by the action of centrifugal force but the instant one of the controlling parts attempts to move individually it is effectively held against movement by the engagement of its controlling-plates. The action of this improved fuse is, as stated above, broadly considered, the same as in my prior forms of fuse, the main differences being in details of construction by which the fuse can be more economically produced.

I also provide in the improved fuse a device for maintaining the armed position of the fuse after this position has once been assumed during the flight of the shell. This device comprises a locking-ring, which is freely and eccentrically supported upon the enlarged end of the combined firing-pin and securing-pin, so that during the flight of the projectile said locking-ring is caused to whirl around said combination-pin by reason of its eccentricity and gradually work forward upon the pin until it slips off the end of the pin and assumes a position between the end of the pin and the abutment or projection against which the pin is thrown upon the impact of the shell. As soon as this locking-ring is interposed between said combination-pin and the abutment its eccentricity will retain it in this interposed position, and as the space between the pin and abutment is normally—that is, in the locked or safety position of the fuse—less than the thickness of the ring it will be clear that it will be impossible for the combined firing and securing pin to move back into safety position. This device is of material importance, as it reduces the chances of failure upon the impact of the shell.

In order that the invention may be fully understood, I first describe the same with reference to the accompanying drawings, and afterward point out the novelty and particularity in the annexed claims.

In said drawings, Figure 1 is a longitudinal sectional elevation of a fuse embodying my present improvements. Fig. 2 is a transverse sectional view of the same, taken on the line $x-x$, Fig. 1. Fig. 3 is a detail plan view of the delay action shown in Fig. 1. Fig. 4 is a side elevation of the sheet-metal shell of the plunger. Fig. 5 is a view similar to Fig. 1, showing the fuse in armed position. Fig. 6 is a top view of the core of the movable plunger; Fig. 7, a vertical sectional view on line $y-y$ of Fig. 6. Figs. 8, 9, 10, and 11 are respectively a top view, an inner face view, an edge view, and an outer face view of one of the centrifugally-actuated controlling parts. Figs. 12 and 13 are respectively a face view and an edge view of the leaf-spring of a controlling part. Fig. 14 is a detail perspective view of one of the controlling-plates. Figs. 15 and 16 are transverse sectional views of the fuse, taken on a larger scale and showing, respectively, the safety and armed positions of the parts.

My present improvements in fuses are applicable to any form of percussion-fuse, whether it be designed for a "poi it-fuse" or a "base-fuse." I have illustrated my improvements as applied to a base-fuse. 1 is a cylindrical fuse body or casing externally threaded at 2 for securing it in the usual threaded opening in the base of a shell, (indicated at S.) The fuse body or casing has a central longitudinal cavity 3 to receive the movable plunger carrying the operative parts of my improved fuse. This cavity 3 is formed with an annular shoulder 4, upon which rests a circular plate 5, formed with an annular series of openings 6 and a central opening 7, in which rests the stem 8 of a controller or delay-action valve 9. This controller-valve 9 is constructed as fully explained in my prior United States Letters Patent, No. 630,621, dated August 8, 1899, and will not be further explained here, since it forms no part of the present invention, excepting as part of a novel combination and its coaction with the improved fuse. This delay-action valve 9 rests normally as shown in Fig. 1 of the drawings, but is adapted to be forced up against the inner face of the hollow plug 10 when it strikes the target. The plug 10 has a central cavity 11 and a central port or opening 12, leading through it to the space above the perforated plate 5. This cavity 11 and port 12 are closely packed with powder, which is confined by a disk or diaphragm 13, secured in the open end of fuse-casing 1 over the plug 10.

Mounted in the main cylindrical portion of the central cavity 3 of the fuse body or casing

is a longitudinally-movable plunger consisting of a core-piece formed with suitable channels and recesses and a surrounding casing or shell. 15 is the plunger shell or casing, and 16 is the recessed core-piece. The shell 15 is made, preferably, of sheet metal stamped or spun into the desired cylindrical cup shape with one end open. The shell 15 has cut into its cylindrical wall three longitudinally-arranged oblong openings 15^a, which are equidistant apart, and in its end wall a central circular opening 15^b, surrounded by three radially-arranged equidistant openings 15^c.

The plunger core-piece 16 has a central longitudinally-extending socket 17, communicating at one end with an enlarged screw-threaded cavity 18 and communicating at the other end with a cavity 16^c, in which the locking end of the combined firing and plunger-securing pin is supported, as hereinafter explained. Three equidistant longitudinally-extending channels or recesses 24 are also cut into the plunger core-piece 16, said channels or recesses uniting in the pin-receiving cavity 16^c and having their inner walls or faces 24^a inclined with relation to the longitudinal axis of the plunger for the purpose which will presently appear. The longitudinal ports or channels 24^b, which are cut into the core-piece, lead from the contracted ends of recesses 24 to the end of the plunger for the purpose hereinafter explained.

A removable screw-threaded hollow plug 19, carrying a primer 20 of any suitable construction, is screwed into the threaded cavity 18 to present the primer 20 at the end of socket 17. The cavity 18 beneath plug 19 and the cavity of the plug are packed with powder held in place by disk 18^a, as shown.

The core-piece 16 is fitted in the shell 15, so that the longitudinal walls of the core channels or recesses 24 will register with the longitudinal walls of the shell-openings 15^a, the open end of the shell 15 being then upset or swaged inwardly over the beveled end of the core-piece to rigidly unite the core-piece and shell to form the plunger.

21 is the combined firing-pin and plunger-securing pin, formed with a reduced firing end 21^a and an enlarged head having an angular locking-shoulder 21^b and a beveled end 21^c. The reduced end of the pin fits loosely in the socket 17 of the plunger and is adapted when properly operated, as hereinafter explained, to come into contact with and detonate the primer 20. The enlarged head of pin 21 rests in the cavity 16^c in operative relation to the controlling devices, which will now be described.

Resting in the angular longitudinal recesses 24 of the plunger are three controlling parts 25. Each of these controlling parts is of proper size and shape to loosely fit within one of the recesses 24, as shown in Figs. 1, 5, 8, 9, 10, and 11, the lower end of each part

resting upon the lower edge of one of the oblong openings 15^a of the plunger-shell to support the part in operative position, while the inner face of each controlling part is cut on a slight angle to rest against the angular inner face 24^a of the recess 24.

The contiguous complementary angular faces 25^x of the locking ends of the controlling parts 25 are cut on lines radial to the axis of the plunger 15 16 (assuming the parts 25 to be in locked position, as shown in Figs. 1 and 15) to allow the said parts to fit snugly around the shouldered head of the combined firing and securing pin 21, each part having a curved notch 25^a and a curved recess 25^b, fitting around the reduced portion and enlarged portion, respectively, of pin 21, thereby forming a locking-shoulder which is adapted to engage the annular locking-shoulder 21^b of the pin. The inclined main inner faces of parts 25 rest against the correspondingly-inclined faces 24^a of recesses 24 to cause the locking ends of the parts to assume their locking engagement with the pin 21. The outer faces of the controlling parts are curved to correspond with the curvature of the cavity 3 of the fuse-body 1, each part having cut into its outer curved surface a longitudinal groove 25^c, in which is mounted a small leaf-spring 26, the end 26^a of which is secured to the part by swaging the walls of groove 25^c upon it. The free end of each spring 26 engages the cylindrical plunger-shell 15 above the upper end of one of the openings 15^a to give the controlling parts a normal spring tendency to move inwardly into locked position. The upper portion of the outer surface of each controlling part is cut away at 25^f to allow the free movements of the controlling parts into released position, as shown in Fig. 5, in which position the main part of the outer curved surface of each part 25 projects through the oblong opening 15^a of the plunger-shell and frictionally contacts with the wall of the cavity 3 of the fuse-body. Each part 25 is also formed with a shallow groove 25^b in its inner face adjacent to its small end for the purpose of providing a port or passage-way for the flash from the primer, which passes through ports 24^b of the plunger. This will be hereinafter more fully explained.

To prevent the accidental individual movement and insure the simultaneous unlocking movement of the controlling parts under the action of centrifugal force, I provide a series of controlling-plates arranged to move radially upon the plunger and having sliding angular engagement with the controlling parts. In their movement from locked to unlocked position the controlling parts move in planes radial to the axis of the plunger and at angles of one hundred and twenty degrees apart. In the upper or locking end of each controlling part 25 I cut two grooves or channels 130

25^d, which extend at an angle of sixty degrees to each other—i. e., each groove or channel extends at an angle of thirty degrees to the radial plane of the plunger in which the controlling part moves. Resting loosely in each contiguous pair of grooves or channels 25^d of adjacent controlling parts 25 is a stamped sheet-metal controlling-plate 27, formed with a central guide lug or shoulder 5 which projects through one of the radial guide-slots 15^c of the plunger. There are three controlling-plates 27, arranged to move laterally in planes radial to the axis of the plunger, one hundred and twenty degrees 10 apart. The core-piece 16 has recesses 16^b cut into the portion of the core which separates the recesses or channels 24 for the purpose of allowing room for the lateral movement of the controlling-plates 27. The radial planes in which the controlling-plates 20 move are midway between the radial planes in which the controlling parts 25 move, the grooves or channels 25^d of the controlling parts extending in all positions of said parts 25 at right angles to the planes of movement of the controlling-plates 27. By reason of this arrangement it will be observed that so long as all of the controlling parts 25 move outwardly simultaneously and equally the controlling-plates 27 will move outwardly in proportion, allowing the controlling parts to slide upon the controlling-plates. It will also be observed that any tendency of an individual controlling part to move separately 30 will be resisted by the engagement of the controlling-plates. The springs 26 tend to hold the controlling parts 25 and controlling-plates 27 normally in their inner locked position, so as to resist any slight outward opening tendency which might be caused by the 35 accidental rotation of the fuse. The pressure of these springs 26 is readily overcome when the fuse is rotated during the flight of the shell.

40 To insure the retention of the operative parts of the fuse in armed position after the shell equipped with my improved fuse has been fired from the gun and during its flight and before it strikes the target, I provide an auxiliary locking device in the shape of a ring 50 which is of sufficient diameter to loosely surround the enlarged end of the firing-pin 21, above the plunger 15 16. This locking-ring 30 during the flight of the shell equipped 55 with my fuse is caused to whirl or gyrate around the pin 21 by reason of the action of the rotation of the flying shell upon the eccentrically-supported ring. The whirling or gyrating motion of the ring around the pin 21 causes it to gradually creep forward upon the firing-pin until it engages the beveled end 21^c of the pin and the beveled end 8^a of the abutment or stem of the controller-valve 9. In this position the ring 30 wedges between 60 the pin 21 and stem 8 by reason of its whirl-

ing action, as previous to this time the centrifugal force has released the controlling parts from their engagement with the pin, thereby releasing the pin to the action of the ring, which forces it rearwardly into the plunger in armed position. As soon as the pin 21 moves away from the stem 8 the ring 30 will move laterally between said pin and said stem and will be held in this interposed position by reason of the continued rotation of the shell in its flight and will thereby prevent the return of the pin and controlling parts to unarmed position from any cause.

The operation of my improved fuse will be understood from the following explanation: 80 Normally the parts of the fuse are in the position shown in Fig. 1, in which position it will be observed that the combined firing and plunger-securing pin 21 is securely locked against movement in the plunger toward the primer and by reason of the relative of the end of pin with the stem or abutment 8 the plunger is retained in its rearward position in the fuse-casing. When the shell equipped with my improved fuse is shot from the gun, it has imparted to it a rapid rotation as well as a forward impulse. The rapid revolution of the shell as it travels through the gun and afterward through the air tends to throw outwardly the three controlling parts 25; but until the centrifugal force exerted upon these parts is sufficient to overcome the friction of said parts in their supporting sockets or recesses (and this friction is of considerable magnitude while the shell is gaining in velocity in the gun) and the pressure of their springs and the air-cushions formed between said parts and the wall of the fuse-casing said controlling parts will not be moved outwardly. At the moment, however, that the 90 centrifugal force is sufficiently strong to overcome these retarding influences said controlling parts will be thrown outwardly simultaneously in their radial planes, as above explained, which will leave the combined plunger-retaining and firing pin free to move inwardly in the plunger into firing relation with the primer, said pin moving into its armed or firing position soon after its release by reason of the action of the ring 30, as above explained.

The inertia of the plunger and the parts supported thereby tends to move the plunger forwardly in the cavity 3; but the centrifugal force acting upon the controlling parts 100 110 causes them to frictionally engage the wall of the cavity 3, and thereby resist the tendency of the plunger as the shell is retarded more or less by the friction of the air in its flight. During the flight of the shell 115 the delay-action valve 9 gradually moves up against the plug 10 by reason of its inertia, as the shell is retarded by the friction of the air. When the shell strikes the target, the plunger 15 16 is forcibly thrown forward,

while the pin 21 is held against any material movement by its engagement with the ring 30, which engages the stem 8, so that the primer will be detonated by the pin, causing the flash to pass through the port 24^b and groove 25^c, up through the central cavity 16^e of the plunger, out through the radial openings 15^a to the cavity of the fuse-casing, and through the series of openings 6 in ring 5, where it ignites the exposed edges of the powder packed in the delay-action valve 9. As soon as the powder in this delay-action valve burns, the flame and gas generated tend to force the valve rearwardly away 10 from the plug 10 and to pass through the opening 12, thereby igniting the charge of powder 11, packed in the plug 10, which will flash into the bursting charge of the shell. By reason of the violent retardation to which 15 the plunger is subjected during the instant of impact and subsequent passage of the projectile through an armored target the delay-valve is held closely in contact with the rear face of plug 10, and no flame can reach the igniting powder 11. When the shell has emerged from the target, this retarding force instantly ceases and the flame forces the valve open and reaches the ignition charge. Thus the delay is governed by the resistance 20 encountered.

Aside from the novel structure of my improved fuse, specifically considered, I desire to claim, broadly, a percussion-fuse comprising a casing, a firing-pin, a detonating-plunger movably mounted in the casing and movable with relation to the pin, a primer upon the plunger, and automatically-released controlling means also mounted upon or within the plunger. The firing-pin or securing-pin 25 is preferably loose in the casing and movably supported in the plunger; but I do not limit myself to this arrangement of said pin, since it is obvious that the pin can be made secure in the casing or be partly confined without departing from the spirit of my invention.

The automatically-released controlling means upon the plunger are preferably centrifugally actuated and preferably arranged to engage and lock upon the combined securing and firing pin; but I would have it understood that the controlling means upon the plunger may engage some other part—such, for instance, as the casing of the fuse—without departing from my invention.

Having thus described my invention, the following is what I claim as new therein and desire to secure by Letters Patent:

1. In a fuse for projectiles, the combination of a fuse-casing, a firing-pin, a plunger 60 movable with relation to the firing-pin in the casing, a primer carried by the plunger, and automatically-released means also carried by the plunger, and normally holding the plunger against action.

2. In a fuse for projectiles, the combina-

tion of a fuse-casing, a combined securing and firing pin, a plunger movable in the casing with relation to said pin, a primer carried by the plunger, and centrifugally-released means upon the plunger engaging said pin and normally holding the plunger against action.

3. In a fuse for projectiles, the combination of a fuse-casing, a plunger-retaining pin, an inertia-operated plunger movable in the casing with relation to the pin, a primer carried by the plunger, and centrifugally-released means upon the plunger engaging said pin and normally holding the plunger against action.

4. In a fuse for projectiles, the combination of a fuse-casing, a plunger movably mounted in the casing, a primer carried by the plunger, a firing-pin loosely mounted in the casing and movable with relation to the plunger, and automatically-released means upon the plunger engaging the firing-pin and normally holding the primer and firing-pin apart.

5. In a fuse for projectiles, the combination of a fuse-casing, a plunger movably supported in the fuse-casing, a primer mounted upon the plunger, a combined securing and firing pin loosely mounted in the casing and movable with relation to the plunger, and automatically-released means mounted upon the plunger and normally engaging the pin to hold the pin away from the primer and the plunger in inactive position in the casing.

6. In a fuse for projectiles, the combination of a fuse-body, and an inertia-operated plunger movably supported in the fuse-body, a primer carried by the plunger, with a plunger-retaining pin movably mounted in the plunger and adapted to engage a suitable stop or abutment, and automatically-released controlling means mounted upon the plunger and engaging the pin.

7. In a fuse for projectiles, the combination of a fuse-body, a plunger movably supported in the fuse-body, a primer, a combined firing-pin and plunger-securing pin movable with relation to the fuse-body and plunger, and centrifugally-operated controlling means mounted upon the plunger and adapted to normally lock said firing and securing pin in its inactive plunger-securing position.

8. In a fuse for projectiles, the combination of a fuse-casing, a firing-pin, a plunger supported in the casing and movable with relation to the firing-pin, a primer carried by the plunger, and a plurality of centrifugally-released controlling parts upon the plunger engaging the firing-pin and normally holding the primer and firing-pin apart, said controlling parts being free to move simultaneously and incapable of individual movement.

9. In a fuse for projectiles, the combination of a fuse-casing, a combined plunger se-

curing and firing pin, a plunger supported in the fuse-body and movable therein with relation to said pin, a primer mounted upon the plunger in operative relation to the firing-pin, a plurality of centrifugally-released controlling parts mounted upon the plunger and normally engaging the pin to hold the pin and the primer apart and the plunger in inactive position in the casing, and means normally preventing the movement of the controlling parts and adapted to automatically release them when they are moved simultaneously by centrifugal force.

10. In a fuse for projectiles, the combination of a fuse-body, and an inertia-operated plunger movably supported in the fuse-body and carrying a primer, with a plunger-retaining pin movably mounted in the plunger and adapted to engage a suitable stop or abutment in the fuse-body, a plurality of centrifugally-released controlling parts upon the plunger engaging the pin, and means adapted to insure the simultaneous movement of the controlling parts, and normally prevent 25 the individual movement of said controlling parts.

11. In a fuse for projectiles, the combination of a fuse-casing, a securing-pin, a plunger movable in the casing with relation to said pin, a primer carried by the plunger, a plurality of controlling parts engaging said pin and arranged to move in planes radial to the axis of the plunger, and means normally preventing the individual movement of the 35 controlling parts and compelling the simultaneous movement of said parts when they are operated.

12. In a fuse for projectiles, the combination of a fuse-casing, a securing-pin, a plunger movable in the casing with relation to said pin, a primer carried by the plunger, a plurality of movable controlling parts mounted on the plunger to engage the securing-pin and arranged to move in planes radial to the 45 axis of the plunger, and means normally preventing individual movement of the controlling parts and compelling the simultaneous movement of said parts when they are acted upon by centrifugal force.

13. In a fuse for projectiles, the combination of a fuse-body, a combined firing-pin and plunger-securing-pin, an inertia-operated plunger movably supported in the fuse-body and movable with relation to said pin, a primer, a plurality of controlling parts mounted upon the plunger in position to engage said pin and arranged to move in planes radial to the axis of the plunger, and means adapted to prevent the individual movement 55 of said parts and compel the simultaneous movement of said parts under action of centrifugal force.

14. In a fuse for projectiles, the combination of a fuse-body having a plunger-supporting cavity, an inertia-operated plunger mov-

able in said cavity, a primer, a pin movably mounted upon the plunger, a plurality of controlling parts mounted upon the plunger in position to engage and control said pin and movable in planes radial to the axis of the 70 plunger, said controlling parts being adapted to frictionally engage the wall of the plunger-supporting cavity when they are operated, and means engaging said controlling parts adapted to normally prevent their individual movement and, when operated, to compel their simultaneous movement. 75

15. In a fuse for projectiles, the combination of a fuse-casing, a plunger movably mounted in the casing and formed with a central longitudinal socket and a plurality of recesses arranged in planes radial to the axis of the plunger, a primer mounted upon the plunger, a pin projecting into said longitudinal socket, a plurality of controlling parts movably mounted in said radial recesses, and means engaging said controlling parts adapted to prevent their individual movement and compelling their simultaneous movement. 80

16. In a fuse for projectiles, the combination of a fuse-casing, a plunger movably mounted in the casing and formed with a central longitudinal socket and a plurality of recesses arranged in planes radial to the axis of the plunger, a primer mounted upon the plunger, a pin supported in said longitudinal socket, a plurality of controlling parts movably mounted in said radial recesses and formed with grooves or channels extending at angles of thirty degrees to the planes in 90 which the controlling parts move, and controlling-plates engaging the grooves or channels of said controlling parts and adapted to prevent their individual movement and compelling their simultaneous movement. 95

17. In a fuse for projectiles, the combination of a fuse-casing, a cylindrical plunger movably mounted in the casing and formed with a central longitudinal socket, a plurality of recesses arranged in planes radial to the axis of the plunger and a plurality of radial openings in the end of the plunger, a pin movably supported in the longitudinal socket, a plurality of controlling parts movably mounted in the recesses in position to engage the 100 pin and formed with angular grooves or channels in their ends, and a plurality of controlling-plates resting loosely in the grooves or channels of the controlling parts and formed with lugs which project into said radial openings. 105

18. In a fuse for projectiles, the combination of a fuse-casing, a plunger movably mounted in the casing and formed with a longitudinal socket and a plurality of recesses 110 arranged in planes radial to the axis of the plunger, a pin movably mounted in the longitudinal socket of the plunger, a plurality of controlling parts movably mounted in the recesses in position to engage the pin, and 115

120

125

130

means engaging the controlling parts arranged to prevent their individual movement and permit their simultaneous movement, said plunger being formed with ports or passages leading from its end into said radially-arranged recesses, and said controlling parts having grooves or ports cut in their inner faces.

19. In a fuse for projectiles, the combination of a fuse-casing, a plunger movably mounted in the casing and formed with a central pin-receiving socket and a plurality of recesses arranged in planes radial to the axis of the plunger, a pin movably mounted in said socket, a plurality of controlling parts movably mounted in said recesses in position to engage said pin, each of said controlling parts being formed with a groove in its outer face, springs mounted in the grooves of said controlling parts and engaging the wall of the plunger to hold the controlling parts normally in locked position, and means preventing the individual movement of the controlling parts and permitting the simultaneous movement of said parts.

20. In a fuse for projectiles, the combination of a fuse-casing, a plunger movably mounted in the casing and formed of a cylindrical shell 15, having a plurality of oblong openings 15^a in its cylindrical side and an axial opening 15^b surrounded by radial openings 15^c in its end, and a core-piece 16 having a central longitudinal socket 17 and the recesses 24 arranged in planes radial to the axis of the plunger, a pin 21 projecting into the opening 15^b and socket 17 of the plunger, a plurality of controlling parts 25 movably supported in the recesses 24 in position to engage the pin and formed with grooves or channels 25^d, and a plurality of controlling-plates 27 engaging the grooves or channels 25^d in said controlling parts and having lugs projected into said radial openings 15^c.

21. In a fuse for projectiles, the combination of a fuse-casing, a plunger movably mounted in the casing and having a central longitudinal socket 17 and the recesses 24 arranged in planes radial to the axis of the plunger, a pin 21 projecting into the socket 17 of the plunger, a plurality of controlling parts 25 movably supported in the recesses 24 in position to engage the pin and each part 25 being formed with grooves or channels extending at angles of thirty degrees to the radial plane of the plunger in which said part moves, and a plurality of controlling-plates 27 engaging the channels cut in said controlling parts.

22. In a fuse for projectiles, the combination of a fuse-casing, a plunger movably mounted in the casing, and formed of a cylindrical shell 15 having a plurality of oblong openings in its cylindrical side and a core-piece 16 having a central longitudinal socket 17 and the recesses 24 arranged in planes ra-

dial to the axis of the plunger, a pin 21 projecting into the socket 17 of the plunger, a plurality of controlling parts 25 movably supported in the recesses 24 in position to engage the pin, springs 26 secured to the controlling parts and engaging the inner wall of the shell 15 to normally hold the controlling parts in their inner engaged position, and automatically-released means preventing the individual movement and permitting the simultaneous movement of the controlling parts under the action of centrifugal force.

23. In a fuse for projectiles, the combination of a fuse-casing, a plunger movably mounted in the casing and formed with a central longitudinal socket and a plurality of recesses arranged in planes radial to the axis of the plunger, a primer, a pin movable in the central socket of the plunger and formed with a locking-shoulder, a plurality of controlling parts formed with locking-shoulders and movably supported in the recesses in position to engage the locking-shoulder of the pin, and means controlling the operation of the controlling parts.

24. In a fuse for projectiles, the combination of a fuse-body, and the plunger and pin supported in the fuse-body and axially movable relatively to place them in armed position, with automatically-released controlling means normally preventing relative movement between the plunger and pin, and centrifugally-operated means freed by said controlling means and adapted to lock the relatively movable plunger and pin in armed position.

25. In a fuse for projectiles, the combination of a fuse-body, a plunger carrying a primer and a firing-pin, the plunger and firing-pin being capable of relative axial movement in the fuse-body to place them in armed position, with centrifugally-released controlling means normally preventing relative movement between the plunger and firing-pin, and centrifugally-operated locking means freed by said controlling means and adapted to lock the relatively movable plunger and pin in armed position.

26. In a fuse for projectiles, the combination of a fuse-body, a plunger carrying a primer, and a firing-pin, the plunger and firing-pin being capable of relative movement in the fuse-body to place them in armed position, with centrifugally-released controlling means normally preventing relative movement between the plunger and firing-pin, and a part supported eccentrically upon the firing-pin and adapted to be operated by centrifugal force to lock the relatively movable plunger and pin in armed position after they are released by the controlling means.

27. In a fuse for projectiles, the combination of a fuse-body, a plunger carrying a primer and movably mounted in the fuse-body, a pin movably mounted in the plunger, a

ring eccentrically supported upon the pin, and automatically-released controlling parts normally engaging the pin.

28. In a fuse for projectiles, the combination of a fuse-body, a plunger, a primer, and a firing-pin, the plunger and firing-pin being capable of relative movement in the fuse-body to place them in armed position, with automatically - released controlling means normally preventing relative movement between the plunger and pin, and a rotatable radially-movable device independent of the plunger and adapted to lock the relatively movable plunger and pin in armed position after the releasing action of the controlling means.

29. In a fuse for projectiles, the combination of a fuse-body, a plunger, a primer, and a firing-pin, the plunger and firing-pin being capable of relative movement in the fuse-body to place them in armed position, with centrifugally-released controlling means normally preventing relative movement between the plunger and pin, and an eccentrically-rotating device independent of the plunger and movable radially of the plunger to lock the relatively movable plunger and pin in armed position.

30. In a fuse for projectiles, the combination of a fuse-body, a plunger, a primer, and a firing-pin, the plunger and firing-pin being axially movable relatively to place them in armed position, with centrifugally-released controlling means normally preventing relative movement between the plunger and pin, and an eccentric device supported to rotate independently of the plunger around the axis

of the plunger and arranged to be moved by its rotation into position to be shifted radially of the plunger by centrifugal force, said radial movement of said device placing it in position to lock the relatively movable plunger and pin in armed position.

31. In a fuse for projectiles, the combination of a fuse-body, a plunger movably mounted in the fuse-body, a primer carried by the plunger, an abutment supported in the casing, a securing-pin movably mounted in the plunger and supported thereby in position to engage said abutment, a locking-ring eccentrically supported upon the pin and adapted to be interposed between the pin and abutment and automatically - released controlling parts normally engaging the pin.

32. In a fuse for projectiles, the combination of a fuse-casing, a plunger movably supported in the casing, a primer carried by the plunger, a pin movably mounted in the plunger and formed with a beveled end, a stem or abutment supported in the casing in position to engage the projecting end of the pin, a locking-ring loosely surrounding the projecting end of the pin and adapted to be whirled upon the pin during the flight of the shell to be moved between the pin and said abutting stem, and automatically - released means upon the plunger normally holding the pin against movement.

HENRY P. MERRIAM.
